US00D553280S

(12) **United States Design Patent** (10) **Patent No.:** **US D553,280 S**
Krieger et al. (45) **Date of Patent:** **** Oct. 16, 2007**

(54) **LANTERN WITH SWIVEL HANDLE**

(57) **CLAIM**

(75) Inventors: **Michael Krieger**, Miami Beach, FL (US); **Kevin Ellsworth**, Hollywood, FL (US)

The ornamental design for a lantern with swivel handle, as shown and described.

(73) Assignee: **Vector Products, Inc.**, Plantation, FL (US)

DESCRIPTION

(**) Term: **14 Years**

(21) Appl. No.: **29/196,995**

(22) Filed: **Jan. 9, 2004**

(51) **LOC (8) Cl.** **26-02**

(52) **U.S. Cl.** **D26/44; D26/46; D26/37**

(58) **Field of Classification Search** D26/37, D26/38, 41, 44, 46, 48, 50, 51, 52, 63; 362/612, 362/157, 158, 159, 183, 192, 193, 208, 200

See application file for complete search history.

FIG. 1 is a perspective view from the front-top-right side of the lantern with swivel handle showing a first embodiment of our new design;

FIG. 2 is a front view of the design shown in FIG. 1;

FIG. 3 is a rear view of the design shown in FIG. 1;

FIG. 4 is a left side view of the design shown in FIG. 1;

FIG. 5 is a right side view of the design shown in FIG. 1;

FIG. 6 is a top view of the design shown in FIG. 1;

FIG. 7 is a bottom view of the design shown in FIG. 1;

FIG. 8 is the perspective view shown in FIG. 1 with the flashlight being in an open position;

FIG. 9 is a perspective view from the front-top-right side of the lantern with swivel handle showing a second embodiment of our new design;

FIG. 10 is a front view of the design shown in FIG. 9;

FIG. 11 is a rear view of the design shown in FIG. 9;

FIG. 12 is a left side view of the design shown in FIG. 9;

FIG. 13 is a right side view of the design shown in FIG. 9;

FIG. 14 is a top view of the design shown in FIG. 9;

FIG. 15 is a bottom view of the design shown in FIG. 9; and,

FIG. 16 is the perspective view shown in FIG. 9 with the flashlight being in an open position.

The broken lines form no part of the claimed design.
